CLIFFORD E. WOLFE, OF BERKELEY, CALIFORNIA, ASSIGNOR OF ONE-HALF TO FRANCIS J. CLAPHAM, OF BERKELEY, CALIFORNIA

BRACKET CLAMP

Application filed December 15, 1930. Serial No. 502,451.

My invention relates to clamps, and particularly to a device for holding a plurality of mutually perpendicular, or skewed bars or the like to form a bracket.

An object of my invention is the provision of a bracket clamp to be used for supporting an object, such as a radiator, on furred walls.

Another object of my invention is the provision of a clamp that may be mounted on a stud fixed in the base wall, to provide a support for a body mounted adjacent the exterior surface of the furring.

Another object of my invention is the provision of adjustable means on the clamp for accurately positioning the external body so that the adjacent furring will not be crushed.

A further object of my invention is the provision of means within the clamp for attaching braces that will hold the radiator in position permanently.

A still further object of my invention is the provision of a clamp that is held together by only one bolt.

The invention possesses numerous other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

Figure 1 is a vertical section through a furred wall showing the manner in which the device of my invention may be used to support a radiator.

Figure 2 and Figure 3 are longitudinal views of the inside faces of the clamp halves.

Figure 4 is a plan view looking down on top of the clamp showing the manner in which the two halves and the adjustable collars fit together.

Figure 5 is a longitudinal view of the clamp looking in the direction of arrow 5 of Figure 4.

In terms of broad inclusion the clamp of my invention comprises a pair of matched jaws which are adapted to engage a plurality of bars that are mutually perpendicular to one another, or that lie in different non-parallel planes in a manner commonly defined as skewed. Such clamps may be used for a variety of purposes but will be described in conjunction with a bracket support for mounting radiators on furred walls where the plaster, or similar sheathing, is supported by a suitable frame work at a distance from the wall.

Such furring is not strong enough, ordinarily, to support a radiator, and it is necessary to provide additional support from a stronger base. It has been the practice in the past to fix four or more studs or bolts in the masonry or concrete base wall and then affix the external radiator hanger proper to the bolts by suitable threaded collars, or nuts, but there are several defects to such methods.

In the first place the bolts cannot be placed accurately and it is usually necessary to bend one or more of them to obtain proper alignment and spacing. This bending combined with the other rough handling incident to the construction activities usually results in the threads on the bolts becoming so battered that their function is seriously impaired, if not destroyed. The plaster and concrete that fall on the threads are also detrimental to their use.

A second major difficulty under past methods occurs in the matter of length adjustment before the furring is installed. If a bolt is too long it can be cut off, of course, but that is a slow and impractical process under modern competitive conditions; and, if a bolt is too short the only practical remedies, splicing or replacement, are difficult and expensive.

A third major difficulty occurs in the matter of accurately positioning the radiator after the furring is installed and the radiator is being hung in place. The plaster is usually not applied with great accuracy and if it does

not come out to the hanger a space is left between the hanger and the wall and an ugly job results. Or, if the plaster projects beyond the hanger supports, it may be pressed in and broken when the hanger is screwed in place. I have seen areas of plaster three to six feet across broken and cracked in this manner, which naturally entails an expensive repair job with resulting loss of time. The means by which I remedy these difficulties will now be described.

In terms of greater detail the preferred embodiment of my invention comprises a clamp, indicated in Figure 1 by the general reference numeral 6, which is adapted to engage a bolt, or stud 7 fixed in a wall 8. The clamp is preferably given additional vertical support by a leg 9 which has its upper end held in the clamp and its lower end resting on a floor 11, or other suitable support. As two or more clamps are usually employed for each radiator it is also desirable to provide transverse bracing as by a channel 12 which interconnects adjacent clamps, and restrains them in position, particularly during the installation of the furring.

The clamp is fixed onto the stud 7 through the medium of a bolt 13 so that the faces of the bosses 14 and 16 will be in the plane of the exterior surface of the furring. An example of furring is shown in Figure 1 as comprising a metal screen 17 and a layer of plaster 18. The brackets and framework that support the furring are omitted from the drawing for the sake of clarity.

The particular construction of the radiator hanger external to the furring forms no part of this invention as any suitable construction may be used in conjunction with the clamping device, but to illustrate the principle I have shown a hanger comprising a plate 19 having a hook 21 fixed on its lower end to support a radiator 22. The radiator is further supported by a suitable bolt 23 engaging the radiator and the upper end of plate 19. The various adjustable features ordinarily employed in such hangers are omitted from the drawing to avoid unnecessary complexity.

The plate 19 is then attached to the clamp by suitable means such as a screw 24 threaded into a lead sleeve 26 inserted in the boss 16; and a screw 27 threaded into the boss 14. In order to prevent the plate 19 from bearing against the plaster the collars 28 are provided about the bosses 14 and 16 to transmit the pressure from the plate to the clamp. The construction of these collars is best shown in Figures 2 and 4, where it can be seen that two helical surfaces 29 and 31 on the collars engage two similar helical surfaces 32, and 33 on the clamp about the bosses.

The exterior end surface of a collar may then be moved in or out by rotating the

collar about the boss. It is found that, by having the collars fit the bosses fairly tight, and by leaving the engaging surfaces unfinished, there is ordinarily sufficient friction between the collar and the clamp to restrain them in adjusted position, but if this friction is not enough to hold them, it is a simple matter to wedge in a piece of steel between a shoulder 34 on the collars, and a shoulder 36 on the clamp, to prevent the collars from slipping around and in. The collars are restrained from outward movement by the plate 19.

In order to facilitate its installation the clamp 6 is preferably constructed in a particular manner as shown in detail in Figures 2 to 5 inclusive. The clamp preferably comprises two matched jaws 37 and 38 embodying suitable seats for the co-operating members with which it is engaged, and adapted to be held together, when installed, by a single bolt.

A seat 39 is provided for the stud 7 by forming a threaded or roughened semi-circular groove 41 in jaw 37 and a smooth semi-circular groove 42 in jaw 38. The groove 41 engages even battered threads quite securely, and the smooth groove 42 permits the jaw 38 to move relative to the lug 7 while the clamp is being set, for reasons to be set forth below. Suitable lugs 43, 44 and 46 are provided on the jaw 37 to fit between the flanges 47 of the channel forming the leg 9; and suitable shoulders 48 are provided on jaw 38 to engage the outside web of the channel 9.

The transverse brace 12 is inserted in the notches 49 and 51 in the jaws 37 and 38 respectively. It is obvious that the stud 7 and leg 9 are tightly engaged by the clamp when the jaws are pulled together by the bolt 13 inserted in the aligned holes 52 and 53, but special provision must be made to cause the clamp to hold the brace 12. In the embodiment disclosed, I accomplish this result through the transverse movement imparted to the jaw 38 by the inclined lugs 54 and 56 sliding on the inclined surfaces 57 and 58 as the jaws are drawn together by the bolt. This causes the face 59 forming one side of notch 51 to press the brace 12 tightly against the face 61 forming one side of notch 49 and thus clamp the brace 12 in place.

It is to be noted that the bosses 14 and 16 are both formed integrally with the jaw 37 so that the movement of jaw 38 will not disturb the original placing of jaw 37 relative to the wall. It is preferable that the bosses fall in the same plane as stud 7 and they are so mounted on the jaw, suitable grooves 62 being formed in jaw 38 to receive them. To further reinforce jaw 38 against vertical deflections a shoulder 63 is formed on its inner face to engage a shoulder 64 provided on jaw 37. It is thus seen that the clamp co-acting with the other elements is locked into a uni-

tary structure by the action of the single bolt 13.

In use, the studs 7 are installed in the wall, preferably when it is constructed, at the proper points. The clamps 6 with the co-operating legs and braces, if used, are next installed so that the faces of the bosses 14 and 16 lie slightly inside a plane that is to be the exterior surface of the furring, which 10 obviates all of the difficulties previously encountered in adjusting the positions of the studs, and also difficulties due to battered threads. The furring is then installed, leaving suitable apertures about the bosses 14 and 15 16. The collars 28 are then placed on the bosses and adjusted as to position, and the external body hung in place.

By using this device of my invention radiators can be installed on furred walls at a fraction 20 of the expense formerly incurred. The saving may amount to as much as three to five dollars for each radiator for labor alone, which will amount to a total saving of several thousand dollars on a large hotel or office 25 building. And, if the studs have been inaccurately placed in the base wall, as is frequently the case, the use of this clamp of my invention will save many thousands of dollars by preventing the crushing of the furring 30 that would otherwise occur.

I claim:

1. A clamp comprising a pair of matched jaws in which a plurality of skewed bars may be seated, inclined guides on the jaws to 35 cause relative displacement as they are drawn together, and means for drawing the jaws together to lock them on the bars.
2. A radiator hanger comprising a fixed supporting stud, a leg, a transverse brace, a 40 pair of matched jaws in which the stud, leg and brace may be seated, means for securing the jaws together to lock them upon the stud leg and brace, and means disposed on the jaws for suspending the radiator.
3. A radiator hanger comprising a fixed supporting stud, a pair of matched jaws in which the stud may be seated, means for securing the jaws together to lock them upon the stud, a boss on the jaws providing means 50 for suspending the radiator, and a wedge shaped collar about the boss providing means for adjusting the position of the radiator.
4. A radiator hanger comprising a fixed supporting stud, a leg, a transverse brace, a 55 pair of matched jaws in which the stud, leg, and brace may be seated, a bolt passing through the jaws, wedging means on the jaws for locking them upon the stud, leg, and brace when the bolt is tightened, and means disposed on the jaws for suspending the radiator.
5. A radiator hanger comprising a fixed supporting stud, a leg, a transverse brace, a 60 pair of matched jaws in which the stud, leg, and brace may be seated, a bolt passing

through the jaws, wedging means on the jaws for locking them upon the stud, leg, and brace when the bolt is tightened, a boss on the jaws providing means for suspending the radiator, and a wedge shaped collar about the 70 boss providing means for adjusting the position of the radiator.

In testimony whereof, I have hereunto set my hand.

CLIFFORD E. WOLFE.
